UNITED STATES PATENT OFFICE.

EDWARD J. SCHNEIDER, OF ST. LOUIS, MISSOURI.

FLUSHING RECEPTACLE.

Application filed August 31, 1921. Serial No. 497,183.

To all whom it may concern:

Be it known that I, EDWARD J. SCHNEIDER, a citizen of the United States, residing at St. Louis, Missouri, have invented a new 5 and useful Flushing Receptacle, of which the following is a specification.

This invention relates to flushing receptacles.

An object of the invention is to provide a 10 flushing receptacle for use as a cuspidor or the like, comprising a bowl or basin for receiving the waste and provided with a hinged lid or cover which, when opened causes water to be discharged into the bowl 15 or basin around the upper portion thereof to flush the same.

Another object of the invention is to provide a flushing receptacle of the character and embodying the construction mentioned, 20 adapted to be mounted in the floor and having a communication through a trap with the waste pipe.

Other objects will appear from the following description, reference being made to the 25 drawing which is a sectional view showing one embodiment of the invention.

As shown, the device includes a bowl or 30 basin 1 which may be made of porcelain or other appropriate material having a discharge opening 2 through the bottom thereof, and provided with a trap 3. The trap 3 has an extended portion 4 adapted to be connected to a waste pipe.

Within and near the top of the bowl or 35 basin a circumferential trough 5 is formed, the outer wall 6 of which rises a considerable distance above the inner wall 7 and is provided with a circumferential flange 8 adapted to support the device within the 40 proper opening in the floor. An internal flange 9 extends from the wall 6 above the upper edge of the inner wall 7 of the trough, leaving a space 10 through which water may flow from the trough to flush the 45 entire inner surface of the wall of the receptacle.

A lid or cover 11 is united to the receptacle by a hinge device 12 and fits within the 50 open upper end of the receptacle. A soft material gasket 13 is preferably located upon the flange 9 to support the lid or cover in its closed position and to prevent noise when the lid or cover is dropped to its closed position.

55 The side of the receptacle at which the

hinge 12 is located is provided with a water inlet passage 14 opening into the trough 5 below the flange 9, so that when water is admitted into the trough under pressure from a water line, the flange 9 serves as a 60 baffle to deflect the water into the receptacle causing the water to wash and flush the entire inner surface thereof. A fitting member 15 is secured to the receptacle and is provided with a part 16 adapted to be connected to a water pipe. A part 16 has an opening 17 therein communicating with an angular passage 18 which in turn communicates with the passage 14 to admit water, 70 as described.

A valve stem 19 is supported by the fitting 15 and is provided with a valve 20 for closing communication between the opening 17 and the passage 18. A reduced portion on the valve stem permits the water to flow 75 through the passage 18 when the valve stem is depressed to open the valve 20. A spring 21 encircles the outer portion of the valve stem 19 having its upper end abutting against a flange 22 on the valve stem and thereby serving to hold the valve 20 in closed adjustment.

A rod 23 is supported in guides 24 formed in integral union with the bowl. The rod 23 has a notch 25 receiving a projection 26 80 on the lid or cover 11. As shown, when the lid or cover 11 is in closed position the rod 23 is supported in its elevated position, out of contact with the head 22 of the valve stem 19. By depressing the rod 23 by the 85 foot, or otherwise, the lid or cover 11 will be raised and the valve 20 will be opened, thereby admitting water into the bowl or basin at the same time that the waste is 90 thrown or deposited therein.

95 Preferably, the outlet opening 2 is covered by a screen 27 to prevent the waste pipe or trap from being choked. The screen is removable.

100 My invention is specially designed and adapted to be built into the floors and to serve the purpose of cuspidors and the like. The construction and arrangement of parts may be varied without departure from the 105 nature and principle of the invention as set forth in the appended claims.

I claim:

110 1. A device of the character described, comprising a bowl, a passage for admitting water into said bowl, a valve controlling

the admission of water into said passage, a stem for said valve, a rod supported for vertical movements into and out of engagement with said stem, a spring for moving the valves to closed position, a lid for the bowl arranged to be closed by gravity, a hinge structure for the lid, and a connection between said lid and said rod whereby movement of said rod to open the valve will open 10 said lid and whereby movement of said lid to closed position will move the rod away from the valve stem.

2. A device of the character described, comprising a bowl, a passage for admitting 15 water into said bowl, a valve controlling the admission of water into said passage, a stem in connection with said valve, a spring in connection with said stem for moving the valve to closed position, a lid for the bowl 20 arranged to be closed by gravity, a hinge device for the lid, a vertically movable rod movable in one direction against the valve stem to open the valve and movable in the opposite direction to permit the valve to 25 close, said rod extending above the lid to

position in which the upper end thereof may be engaged by the foot for downward movement, and a connection between said rod and the lid whereby downward movement of the rod will open the lid and whereby movement of the lid to closed position will move the rod to its initial position. 30

3. A device of the character described, comprising a bowl, a passage for admitting water into said bowl, a valve controlling the 35 admission of water into said passage, a stem in connection with said valve, a spring encircling said stem for closing the valve, a lid for the bowl arranged to be closed by 40 gravity, a hinge device for the lid, a projection rigid with the lid, a rod having a notch in one side thereof to receive said projection, said rod having its upper end above the lid arranged to serve as a pedal for the foot, and means supporting the rod in alignment with the valve stem so that downward movement of the rod to open the lid will 45 also open said valve.

EDWARD J. SCHNEIDER.
